UNITED STATES PATENT OFFICE.

NICOLAUS J. MAY, OF SAN FRANCISCO, CALIFORNIA.

PUZZLE.

Application filed November 27, 1922. Serial No. 603,484.

To all whom it may concern:

Be it known that I, NICOLAUS J. MAY, a citizen of the United States, residing at San Francisco, in the county of San Francisco and State of California, have invented new and useful Improvements in Puzzles, of which the following is a specification.

This invention relates to improvements in geometrical puzzles and resides in the provision of a highly amusing and novel form of puzzle which takes into consideration the contradistinction of colors, characters or other indicia, in the solving of the puzzle.

The primary object of the invention is to provide a puzzle of the character described which will prove instructive, entertaining and which will afford a means of testing the mental efficiency of applicants for positions and for other general purposes of this nature, there being a plurality of puzzle pieces which may be made of wood, card-board or other material, of irregular outline arranged so that when assembled in proper order a definite geometrical figure will be produced, each piece bearing like characteristics and being of similar appearance on one side and having a different but corresponding appearance or indicia on the other side thereof. For example, each puzzle piece will be white on one side and red on the other side. In employing this contradistinction of color, or contradistinction of indicia feature, the person attempting to solve the puzzle is misled. If the arrangement of the pieces is such that when attempting to solve the puzzle with the pieces of all one appearance, face up, the puzzle can not be solved, it being necessary to have one puzzle piece appear in contradistinction with the other pieces as to color or indicia in order to solve the puzzle.

The invention may also be used to advantage for advertising purposes.

The invention possesses other advantages and features some of which, with the foregoing will be set forth at length in the following description where I shall outline in full that form of the invention which I have selected for illustration in the drawing accompanying and forming a part of the present specification. In said drawing I have shown one form of the construction of my invention, but it is to be understood that I do not limit myself to such form since the invention as expressed in the claims may be embodied in a plurality of forms.

Referring to the drawing:

Figs. 1, 2, 3 and 4 represent top plan views of the respective pieces of the puzzle, there being four of such pieces.

Fig. 5 represents a plan view of the puzzle pieces as when assembled but in improper order, the faces of the pieces corresponding as to appearance.

Fig. 6 represents a top plan view of the puzzle as when correctly solved, showing one of the pieces in contradistinction in appearance to the others, for example, one piece with the red side showing and the other pieces with the white sides showing.

In carrying out my invention, I cut or otherwise form, angular pieces of such a nature that when properly assembled a definite geometrical figure such as a square, rectangle or the like, will be provided and such that one of the pieces will have an appearance in contradistinction to the remaining pieces. In the embodiment of the invention shown in the drawing, I have selected a square as the geometrical figure to be produced by properly placing together the pieces of the puzzle. I have provided four pieces, designated 1, 2, 3 and 4. One way in which I may arrange for the contradistinction in appearance feature of the puzzle is to provide, as shown, each piece of one color on one side, for example white, and of another color on the other side, for example red. If the puzzle pieces were cut or formed from a piece of card-board or wood, which, for example is red on one side and white on the other, said pieces could be fitted together and the puzzle solved very easily with the exposed faces of the pieces of like appearance. However, to make the puzzle amusing and entertaining, that is, more difficult to solve, one of said pieces, for example, the one 4, is discarded but replaced by a piece of the same shape, size and appearance, except that it is cut from the material with the opposite color uppermost, whereby in order to solve the puzzle, said piece must necessarily be placed with the side thereof uppermost in contradistinction to the color of the other pieces.

As shown in Fig. 5, the pieces 1, 2, 3 and 4, are assembled with the white sides uppermost, that is provided that a white side is to be employed as a means of giving each piece the same appearance on one side. However, it is to be understood that indicia

may be used, of any sort and various other colors employed but so that each piece will be of the same appearance on one side.

The psychological effect in solving the puzzle is such that the person attempting to solve it will, unconsciously be influenced to do so with the pieces laid on a table or other support with the colors or other indicia corresponding. For example, the pieces are laid in front of the person attempting to solve the puzzle with the white sides of the pieces uppermost. The person is unconsciously influenced in attempting to solve the puzzle to keep the pieces with the white side uppermost and moves them in various positions in order to solve the puzzle. It is not likely to occur to the person to reverse one piece and arrange the group of pieces with their white sides uppermost and the reversed piece with its red side uppermost. The effect of this contradistinction is such that it will cause the person solving the puzzle to arrive at the conclusion that the assemblage of the pieces is improper unless the reversed piece is laid near and in proper relation to the other pieces.

In Fig. 6, the puzzle is shown as when the pieces are carefully put together, in this instance, the piece 4 is reversed from the position as shown in Fig. 5, which brings its red side uppermost, whereas the remain-

ing pieces remain with their white side appearing. It is contended that in the handling of the pieces in attempting to solve the puzzle, one would be influenced to avoid reversing the pieces 3 and 4, since a contrast in colors would be apparent. However, should one solving the puzzle, place the piece 4 close to and in proper relation to the other pieces rather than hold it in the hand, it will be apparent that the figure produced is a square and that the puzzle is solved. It will thus be seen that the principal feature of this invention extends into the use of puzzle pieces of such relation and appearance that the correct arrangement of such pieces depends upon their being laid with one piece of an appearance contrasting with the other pieces.

I claim:

A puzzle consisting of four pieces which when laid in proper relation will form a predetermined figure of rectilinear outline, the face sides of said pieces being of the same color and the reverse sides being of a different color, said pieces being so shaped that when all are laid with the face sides uppermost, a figure other than that predetermined will be produced and when properly laid to form the predetermined figure, one of the pieces is required to be reversed.

NICOLAUS J. MAY.
